(57) **CLAIM**

The ornamental design for a tangential flow filtration benchtop purifier as shown and described.

DESCRIPTION

FIG. 1 is a front, left perspective view of a tangential flow filtration benchtop purifier showing our new design;

FIG. 2 is a front elevation view thereof;

FIG. 3 is a rear elevation view thereof;

FIG. 4 is a left side elevation thereof;

FIG. 5 is a right side elevation view thereof;

FIG. 6 is a top plan view thereof; and,

FIG. 7 is a bottom plan side view thereof.

In the drawings, the broken lines depict portions of the tangential flow filtration benchtop purifier that form no part of the claimed design.
